CASKET HANDLE

John Pastor and Louis J. Standish, Bridgeport, Conn., assignors to The Bridgeport Casket Hardware Company, Bridgeport, Conn., a corporation of Connecticut

Application August 22, 1942, Serial No. 455,768

4 Claims. (Cl. 16—112)

1

This invention relates to a casket handle and has for an object to provide an improved and simple construction particularly adaptable for construction from wood, and which is so constructed and arranged that the lifting weight or strain on the handle is taken independently of the hinge pin and is so applied to the handle as to tend to press the opposite sides thereof together so that there is no tendency for the handle to split and thus fail to support the casket being carried.

It is also an object to provide such a construction which can be made entirely of wood and does not require reinforcing with metal.

With the foregoing and other objects in view we have devised the construction illustrated in the accompanying drawing forming a part of this specification. It is, however, to be understood that the invention is not limited to the specific details and arrangement shown but may comprise various changes and modifications within the scope of the invention.

In this drawing:

Fig. 1 is a side elevation of the handle applied to a casket, a portion of the casket being shown in section;

Fig. 2 is a front view thereof;

Fig. 3 is a section substantially on line 3—3 of Fig. 2 on a somewhat larger scale and showing the handle in raised or carrying position;

Fig. 4 is a front view of the lower portion of the lug with the pivoted handle portion removed;

Fig. 5 is a bottom view thereof, and

Fig. 6 is a rear view.

This handle may be made of different material but due to the scarcity of available metals it is so designed as to be constructed of wood and still have the required strength without requiring metal inserts, and is so constructed and arranged that the weight or strain on the handle acts to prevent splitting of the handle in contrast to former constructions in which strains tend to cause handles to split. The construction is also such that when the handle is in the lifting or carrying position there is no weight and practically no strain on the hinge pin, but all the weight or pressure is carried directly from the lug to the handle, the pin being required merely to keep the elements from separating. The handle comprises the block or lug 10 secured to the casket 11 by any suitable means, such as the screws 12 and 13. This block is provided with a notch or recess 14 extending upwardly from its lower edge in which the handle member or bar 15 is pivoted by a pin 16. Any suitable type of

2

grip bar 17 is mounted on the member 15. It is to be understood that there may be a number of these blocks and pivoted members secured to the side of the casket with a grip bar 17 connecting them, or the members 10 and 15 may be mounted in pairs with a short grip mounted on the individual handles. Block 10 is transversely recessed in its rear wall at its lower end, as indicated at 18, for a transverse insert block or strip 19 of hard wood. The inner end of the bar is shaped as shown in Figs. 1 and 3. It is slightly recessed at the inner end on the under side, as indicated at 20, providing a shoulder 21 to rest on top of the insert piece 19 when the handle is in the raised or carrying position, and at the top side of the bar is a transverse supporting surface 22 to engage the surface 23 at the top of the notch or recess 14. It will be seen from Fig. 3 that the surface 22 is at the right or outwardly of pivot pin 16, so that as the bar 15 is raised it is carried upwardly and engages against the surface 23 and the surface 23 therefore presses downwardly on the surface 22. It will also be seen that the surface 21 is on the opposite side of the pivot 16 or inwardly of it, so that it presses downwardly on insert 19 and pressure of this insert 19 on this surface 21 is upwardly. Therefore the pressures against the two surfaces 21 and 22 are on opposite sides of the bar 15 and tend to press them together so that there are no forces tending to split the bar 15, but in fact there are forces acting just the opposite, tending to press the grain of the bar together.

Just forwardly of the surface 22 there is also preferably provided an upright shoulder 24 to engage the front surface 25 of the block 10. This acts to also press against the block and form a sort of stop, and it also supports the material or grain of the wood of the block 10 just forwardly of the surface 22, and thus prevents the wood yielding outwardly or being crushed by the pressure of the surface 22. It will be seen that when the bar 15 is in the raised or carrying position, the entire weight or strain of lifting and carrying is taken by the surfaces 21, 22 and 24 against the members 19 and 10 so that there is no strain on the hinge pin 16 which would tend to split the bar 15 or shear off this pin, the pin being required merely to retain the bar 15 in the block 10 to prevent their separating. The insert 19 is preferably made of harder or tougher wood so as to take the pressure of the surface 21 without yielding or crushing, thus permitting the block 10 to be made of some softer wood. It is also easier to make this device with the insert 19 as the

notch or recess 14 can then be cut by sawing from the lower edge of the block 10 and the recess for the insert 19 may be cut transversely across the block, and the insert later mounted in position, thus doing away with the necessity of making a square opening through the block for the inner end of the bar 15. The insert 19 may be secured to the block 10 by screws or glue, and the mounting screws 13 are preferably passed through this insert as well as the block 10, thus securing the insert directly to the casket so that there is no danger of its becoming detached therefrom or yielding in lifting or carrying. The surface 21 is inclined slightly as indicated, relative to the lower wall of the bar 15 and the hinge pin, so that the reaction against the top of the insert 19 tends to draw the bar 15 inwardly and thus secure it more firmly in the carrying position instead of tending to force it outwardly.

It will be seen from the above that the handle is of very simple construction and may be made entirely of wood, thus saving metal, which at the present is required for other purposes. However, the structure is such that there is no danger of the wood crushing or failing under the lifting and carrying loads required to be taken care of, and that the strains and pressures are so applied to the handle that instead of tending to split it as in ordinary constructions, they act just the opposite and tend to press the opposite sides of the bar together and obviate any danger of its splitting or otherwise yielding. This is important as it will be understood that in the main use for which the device is intended there should be absolutely no danger of its failing or yielding.

Having thus described the nature of our invention what we claim is:

1. A casket handle attaching device comprising a bracket portion and a rod-carrying hinge member, said bracket portion being slotted to receive said hinge member and said hinge member being pivotally mounted at a point adjacent its upper end upon horizontal pin means, a recess at each side of the slot in the inner face of said bracket portion, and an abutment piece extending across said slot with its ends fitting into said recesses, said abutment piece lying flush with the inner face of the bracket portion whereby it is held in place by the adjacent wall of the casket and being located somewhat below and to the rear of the pin means in position to be engaged by the upper inner portion of the hinge member whereby to stop upward movement of the latter.

2. An all wood casket handle attaching device comprising a bracket portion and a rod-carrying hinge member, said bracket portion being slotted to receive said hinge member and said hinge member being pivotally mounted at a point adjacent its upper end upon a dowel pin extending across said slot, a recess at each side of the slot in the inner face of said bracket portion, and an abutment piece extending across said slot with its ends fitting into said recesses, said abutment piece lying flush with the inner face of the

bracket portion whereby it is held in place by the adjacent wall of the casket and being located somewhat below and to the rear of the dowel in position to be engaged by the upper inner portion of the hinge member whereby to stop the upward movement of the latter.

3. A handle of the character described comprising a lug adapted to be mounted on an article to be carried and provided with a recess extending upwardly from the lower edge thereof and a transverse recess in the rear wall adjacent said lower edge, an insert in said latter recess extending across the lower part of the first recess, and a handle member comprising a wooden bar pivotally mounted in the first recess by a transverse pin extending through the bar, said bar being provided with a contact surface on its upper side located above and outwardly of the pivot pin to engage the top of said recess when said bar is in the raised or carrying position and another contact surface on its lower side located below and inwardly of the pivot pin to rest on said insert to prevent splitting of the bar under action of the pin.

4. A handle of the character described comprising a lug adapted to be mounted on an article to be carried and provided with a recess extending upwardly from the lower edge thereof and a transverse recess in the rear wall adjacent said lower edge, an insert in said latter recess extending across the lower part of the first recess, a handle member comprising a wooden bar pivotally mounted in the first recess by a transverse pin extending through the bar, said bar being provided with a contact surface on its upper side located above and forwardly of the pivot pin to engage the top wall of the recess when the bar is in the raised or carrying position and a second contact surface on its under side located below and rearwardly of the pivot pin to rest on said insert so that the pressures on said surfaces tend to press the upper and lower sides of the bar toward each other to prevent splitting of the bar by pressure from the pin, and an upright shoulder on the top of the bar forwardly of the first contact surface to engage the upright front surface of the block at the top of the first recess.
